UNITED STATES PATENT OFFICE.

EDWARD C. BRICE, OF CHICAGO, ILLINOIS.

CONTINUOUS KILN OR FURNACE FOR BURNING BRICKS, &c.

SPECIFICATION forming part of Letters Patent No. 636,193, dated October 31, 1899.

Application filed June 21, 1899. Serial No. 721,366. (No model.)

To all whom it may concern:

Be it known that I, EDWARD C. BRICE, a citizen of the United States, residing at Chicago, in the county of Cook and State of Illinois, have invented certain new and useful Improvements in Continuous Kilns or Furnaces for Burning Brick or other Material; and I do hereby declare the following to be a full, clear, and exact description of the invention, such as will enable others skilled in the art to which it appertains to make and use the same.

My invention is an improvement in that class of continuous kilns or furnaces in which a series of cars or trucks loaded with bricks or other articles to be burned are passed through a tunnel having fire-boxes arranged along the sides and communicating with the space or heat-chamber above said trucks, so that the products of combustion may be discharged thereinto and upon the bricks. Many unsuccessful attempts have been made to produce furnaces or kilns of this class. The most prominent cause of failure was the defective supply of oxygen, and consequently insufficient combustion along the lower side angles of the heat-chamber, and another cause was the overheating of the wheels and under portions of the trucks by reason of the defective supply of cool atmospheric air thereto while the trucks were in the area of greatest heat in their passage through the tunnel. I have completely overcome these defects by the construction and arrangement of parts hereinafter described and claimed.

In the annexed drawings, Figure 1 represents a side view of a furnace constructed according to the present invention. Fig. 2 represents a vertical longitudinal section of such furnace, taken through the fire-boxes and smoke-stacks. Fig. 3 represents a horizontal longitudinal section of such furnace. Fig. 4 represents a vertical transverse section through the furnace. Fig. 5 represents an end view of such furnace. Fig. 6 represents a vertical longitudinal section taken through the middle of such furnace. Fig. 7 represents in detail one-half of one of the doors or gates. Fig. 8 represents a sectional view of the same. Fig. 9 represents an enlarged detail of the connection between the cars and the tunnel.

Figs. 10 and 11 represent longitudinal and transverse views of the grate-bars.

The furnace or kiln A has a longitudinal passage or tunnel a. In Figs. 3 and 6, A' indicates the entrance end, A² the middle section or body, and A³ the exit end, of the kiln. The tunnel is provided at each end with swinging doors B, which do not extend below the truck-platforms, so that space is provided for admission of air beneath the trucks. The side walls of the tunnel are vertical and the top d is arched or curved, as shown.

Fire-boxes D, Fig. 4, are arranged oppositely at intervals along the sides of the tunnel a and communicate with the latter at the top by means of passages d', which extend through the upper ends of the side walls. These fire-boxes have the usual openings d² for supplying fuel, also ash-pits d³ and grate-bars d⁴. The latter may be constructed with grooves d⁵, as shown in Figs. 10 and 11, for the purpose of avoiding the excessive accumulation of clinkers. Air is supplied to the fire-boxes D in the usual way and also by pipes d⁶, Fig. 3, which lead from a common entrance d⁷ to the several ash-pits d⁸. By means of a valve located at d⁷ the supply of air through the ducts d⁶ may be regulated at will.

Cars or trucks F run on two parallel tracks 80 laid on the bottom or floor of the tunnel, and their platforms are provided with pendent side flanges f, (see Figs. 4 and 9,) which run in troughs e², filled with sand, whereby a practically air-tight seal is produced and communication between the heating-space above the trucks and that below them prevented. It will be noted that there are two outside troughs E and a central or intermediate one G, the latter being arranged upon a low brick 90 partition extending through the tunnel a, between and equidistantly from the parallel tracks. The cars or trucks have metal platforms covered to a suitable depth with fire-proof material whose surface is flush with 95 ledges formed along the sides of the tunnel a, as shown in Fig. 4.

As shown in Fig. 3, there are three smoke-stacks or chimneys C C' C² on each side of the kiln, one being arranged near each end 100 and the other at the middle point of the kiln.

I come now to describe the feature of my

furnace or kiln upon which its superior efficiency mainly depends—namely, the arrangement with and functional relation to the fire-box passages d' of the side flues for the products of combustion and the ducts or passages by which air is supplied to such flues. For convenience of designation I will term the latter "heat-flues."

As shown best in Figs. 3 and 4, a heat-flue C^X 10 extends nearly the whole length of each side wall of the tunnel a , the same being arranged in the base of said wall and preferably in line with the tops of cars or trucks. These flues C^X communicate with the chimneys, as 15 shown, and their cubical capacity is enlarged at points near the chimneys, as shown by dotted lines, Fig. 6. Said flues C^X communicate with the tunnel by numerous lateral passages or short flues c^2 , Figs. 3, 4, and 6.

While in the broadest aspect of my invention I do not wish to restrict myself to the means for admission of atmospheric air along the side angles of the heating-chamber, the means I have found most effective and desirable for several reasons is the small passages c^2 , (see Figs. 3 and 4,) which extend laterally into the side walls of the tunnel at a point below the truck-platforms and then upward to the flues C^X . These passages are 25 shown joined by passages e' , which extend in the side walls parallel to the tunnel; but they are not at all necessary to the successful operation of the furnace. The air entering beneath the end doors B traverses the tunnel 30 beneath the trucks, thus cooling the latter before passing up to the point of combustion of its oxygen.

As shown by arrows, Fig. 4, the products of combustion passing up from fire-boxes D , 40 through their throats d' , tend to converge at the center of the arch d and spread or diverge thence upon the bricks or other material set on the cars F , and then pass down through and around the bricks toward the side flues C^X . At this point the solid and gaseous products of combustion are met by a supply of oxygen furnished by inflowing atmospheric air, which enters the side flues C^X . Careful 45 experiment with and observation of the operation of a full-sized kiln constructed according to this plan has established the fact that not only does this conjunction of oxygen and products of combustion occur in the flues C^X and their lateral passages c^2 , but even outside the latter and within the heat-chamber containing the bricks. In other words, the air admitted to the side flues C^X promotes 50 secondary combustion all along said flues and in their lateral passages, as well as along the adjacent side angles of the heat-chamber. The lateral passage of the air from flues C^X into the heat-chamber seems to be effected 55 intermittently, and hence the action of the kiln, or, rather, the blast, as indicated by the appearance of flame at the top of the chimneys, is pulsatory. The result is most satisfactory and, in fact, remarkable in that the

combustion produced appears practically perfect, while the bricks are thoroughly, evenly, and quickly burned to the desired degree. 70 These results indicate a corresponding economy in fuel.

Experiments made on a large scale have demonstrated that without the downdraft from the fire-box throats d' and meeting the 75 same with a due supply of oxygen in the side angles of the heating-chamber, substantially in the manner described, such results cannot be obtained.

Another important feature remains to be 80 stated—namely, that the air which thus supplies oxygen at a critical juncture in the process of combustion subserves another function on its way to the flues C^X , in that it passes in contact with the wheels and under 85 portions of the truck-frames, and thus effectively cools the same and becomes itself more or less heated, in which condition it enters the flues C^X . Thus two important results are 90 attained—to wit, cooling the trucks and promoting combustion by preliminary heating of the oxygen supplied. If the latter were delivered at any other point than where it may combine with the products of combustion, as before stated, combustion would be 95 promoted ineffectively or but slightly. The air becoming gradually heated, and thus rarefied, as it passes along the tunnel from each end, the tendency of the same to escape at once into such of the side passages c^2 as are 100 nearest the ends of the tunnel is counteracted sufficiently to insure a due supply at the center of the kiln, where chimneys are located and the heat greatest.

Having thus described my invention, what 105 I claim, and desire to secure by Letters Patent, is—

1. The improved furnace or kiln of the character described, comprising a tunnel, fire-boxes arranged on the sides thereof, and having throats or exit-passages leading upward toward the arch of the tunnel, longitudinal heat-flues arranged in the side walls intervening the fire-boxes and tunnel, lateral passages leading from said flues into the tunnel, and other passages for delivering air to support combustion along the side angles of the tunnel adjacent to the car-platforms, substantially as specified. 110

2. The improved furnace or kiln of the character described, comprising a tunnel, fire-boxes arranged on the sides thereof, and having throats or exit-passages leading upward toward the arch of the tunnel, longitudinal heat-flues arranged in the side walls intervening the fire-boxes and tunnel, lateral passages leading from said flues into the tunnel, and a series of air-passages leading laterally and upward from the tunnel-space beneath the trucks, to conjunction with the heat-flues and heat-chamber above the trucks, substantially 115 as specified. 120

3. In a furnace or kiln of the character described, the combination with the tunnel hav-

ing doors which allow free admission of air at each end of the tunnel, fire-boxes located on the sides of the tunnel, and heat-flues arranged in the side walls and communicating with the heating chamber or space above the trucks, of air-passages leading directly laterally from the space below the trucks into the said heat-flues, substantially as shown and described.

5 4. A furnace A, having the fire-boxes D, the tunnel, a, the former communicating with the latter; the smoke-stacks; the heat-flues C^X, communicating with the smoke-stacks; the passages c³, connecting the tunnel and flues; passages e² e³, connecting the flues with the

15 tunnel a, as set forth.

5. The improved furnace or kiln comprising a tunnel adapted for passage of cars loaded with articles to be burned, fire-boxes arranged along the side thereof, side walls intervening them and the tunnel, save at the top, where transverse passages extend through

the walls from the several fire-boxes, flues or spaces arranged in the walls on their inner sides and at their bases approximately at the floor-level of the cars, and passages admitting 25 atmospheric air to said spaces, whereby the products of combustion converging from the fire-boxes descend through the articles on the cars, and, diverging through the lower side angles of the tunnel combustion-space, meet 30 there currents of air supplied to increase combustion and heat at such points, the products of such second or final combustion passing off through the same aforesaid spaces into which the air was received, as specified.

35 In testimony whereof I affix my signature in presence of two witnesses.

EDWARD C. BRICE.
